ROY T. AXE, OF SYRACUSE, NEW YORK, ASSIGNEE TO THE O. M. EDWARDS COMPANY,
INC., OF SYRACUSE, NEW YORK, A CORPORATION OF NEW YORK.

WINDING-ROLLER.

1,322,747.

Specification of Letters Patent. Patented Nov. 25, 1919.

Application filed February 7, 1916. Serial No. 76,677.

To all whom it may concern:

Be it known that I, Roy T. Axe, a citizen of the United States, and a resident of Syracuse, in the county of Onondaga and State 5 of New York, have invented a certain new and useful Winding-Roller, of which the following is a specification.

This invention relates to winding rollers and has for its object a particularly simple 10 and efficient construction whereby a chain or cable which winds on the roller, is readily attached to the roller which chain or cable usually supports a window or other means; and the invention consists in the combinations 15 and constructions hereinafter set forth and claimed.

In describing this invention, reference is had to the accompanying drawings in which like characters designate corresponding 20 parts in all the views.

Figure 1 is an elevation, partly broken away, of a roller embodying my invention, the end portions of a chain attached to the roller being also shown, one end being shown 25 as attached thereto and the other as detached therefrom.

Figs. 2 and 3 are sections taken respectively on lines 2—2 and 3—3, Fig. 1, the end of the chain which is shown as detached in 30 Fig. 1, being shown as attached to the roller in Fig. 3.

Fig. 4 is a detail view of the coupling piece between one end of the chain and the roller.

35 1 designates the roller which may be of any suitable form, size and construction, said roller including a sheet metal tube and having the usual trunnions or axles 2, 3 at its opposite ends, one of which is rigid with 40 the roller and the other of which is connected to a torsion spring not shown, located within the roller as will be understood by those skilled in the art.

The tubular body of the roller 1 is here 45 shown as formed with an opening or openings therein near opposite ends thereof as the slots 4, 5 and also usually with tongues, 6, 7 which tongues are struck up from the body of the roller 1 when the slots are 50 formed, that is, the slots are left in the roller after the tongues 6, 7 are struck or cut out. Preferably, these slots and tongues extend in a direction circumferentially of the roller instead of lengthwise thereof.

8 designates a cable, the opposite ends of 55 which are secured to the roller and the intermediate part of which is usually secured to a window or other part to be raised or lowered or counterbalanced as will be understood by those skilled in the art. 60

Each end of the chain or cable 8 is formed with means extending into the slots 4, 5 respectively, and having a cross bar interlocking with the contiguous part of the tube of the roller 1 on opposite sides of the slots 65 4, 5, after the cross bar is interlocked with the tube, the tongue 6 or 7 which normally occupies the position shown in Fig. 3, is bent into the position shown in Fig. 2 to hold the said means at the end of the chain 70 or cable 8 from undue movement in the slot 4 or 5.

The chain here shown is of that type composed of links which are stamped from sheet metal, the blank for each link being bent 75 upon itself to bring eyes 9 at opposite ends of the link into alignment for receiving the intermediate or looped portion 10 of the next link as will be understood by those skilled in the art. When the chain is complete the eyes 9 of one end link are located at the extreme end of the chain while the loop 10 of the other end link is located at the other extreme end of the chain. Therefore, when a continuous chain is used different forms of coupling means must be provided. 80 85

The coupling means here shown are T-shaped and the T-shaped means connected to the end link in which eyes 9 are in alignment at the extreme end of the chain, consists of a strip 11 having laterally extending heads 12 at its opposite ends, one of these heads being passed through the aligned eyes 9 of the end link and the strip being 90 then bent upon itself bringing the heads 12 into alignment forming a cross bar which is then passed through the slot 4. The coupling 11 is turned so that the cross bar extends on opposite sides of the slot 4 and interlocks with the tubular body of the roller 95 1, as clearly seen in Figs. 1 and 2.

The T-shaped means at the other end of the chain includes a bar 13 passed through the loop portion 10 of the last link at the 105 said end of the chain, this bar having enlargements 14 at its opposite ends which pass into the slot 5 and interlock with the

roller 1 on opposite sides of the slot 5 in a manner similar to the engagement of the heads 12 with the roller 1.

After the T-shaped means are located in the slots 4, 5, the tongues 6, 7 are bent into the position shown in Fig. 2, so that unintentional detachment of the chain from the roller is prevented.

This means for attaching the chains to the roller is particularly advantageous in that it is simple in construction, economical in manufacture and provides for the ready removal and replacement of the chain when necessary.

15. What I claim is:

1. The combination of a winding roller comprising a tube having a tongue struck therefrom forming a slot, and a cable for winding on the roller, the cable having means at one end extending through the slot and interlocking with the portions of the roller contiguous to the slot, the tongue being bent into position to hold said means from removal from the slot, substantially as 25 and for the purpose described.

2. The combination of a winding roller having an internal cavity, and a slot in the periphery thereof opening into the cavity, and a cable for winding on the roller having means extending into the slot and a cross bar of less length than the length of the slot and of greater length than the width of the slot whereby the cross bar can be inserted through the slot into the cavity 35 and turned to interlock therein, and extend beyond the sides of the slot and engage the internal face of the roller on opposite

sides of the slot, the roller also having means on the exterior thereof for engaging the portion of the cable extending through the slot 40 to prevent disengagement of the cable from the roller and holding the cross bar from twisting into a position extending lengthwise of the slot, substantially as and for the purpose described.

45. 3. The combination of a winding roller comprising a tube having a tongue struck therefrom forming a slot, a cable winding on the roller and having means at one end extending into the slot, said means comprising a cross bar located in the roller and the cross bar interlocking with the portions of the roller on opposite sides of the slot, and the tongue being bent into position to partially close the slot and hold the said means 50 from removal, substantially as and for the purpose set forth.

4. The combination of a winding roller comprising a tube having a slot formed therein extending in a circumferential direction thereof, and a cable winding on the roller, and having means at one end extending through the slot and including a cross bar located in the roller, the cross bar extending lengthwise of the roller and on opposite sides of the slot and interlocking with the contiguous portions of the roller, substantially as and for the purpose described.

In testimony whereof I have hereunto signed my name at Syracuse, in the county 70 of Onondaga, and State of New York, this 20th day of January, 1916.

ROY T. AXE.
